(57) **CLAIM**

The design for a lid for lid for drinking container, as shown and described.

DESCRIPTION

FIG. 1 is a front top perspective view of a lid for drinking container;

FIG. 2 is a front view of the lid for drinking container illustrated in FIG. 1;

FIG. 3 is a rear view of the lid for drinking container illustrated in FIG. 1;

FIG. 4 is a right side view of the lid for drinking container illustrated in FIG. 1;

FIG. 5 is left side view of the lid for drinking container illustrated in FIG. 1;

FIG. 6 is a top view of the lid for drinking container illustrated in FIG. 1; and,

FIG. 7 is a bottom view of the lid for drinking container illustrated in FIG. 1.

In the drawings, the broken lines showing a drinking container depict environmental subject matter that forms no part of the claimed design. The broken lines in FIGS. 1 and 6 showing the opening in the lid depict portions of the article that form no part of the claimed design.

1 Claim, 6 Drawing Sheets
